**ADJUSTABLE CUSP CUTTER FOR BORING TYPE
CONTINUOUS MINING MACHINE**

Joseph Gonski, Chicago, Ill., assignor to Goodman Manufacturing Company, Chicago, Ill., a corporation of Illinois

Application July 23, 1957, Serial No. 673,729

5 Claims. (Cl. 262—7)

This invention relates to improvements in continuous mining machines of the boring type particularly adapted for operation in low seams of coal.

A principal object of the invention is to provide an improved form of low continuous mining machine having a simplified and compact adjustable support for the cutting means for cutting out the unmined cusps of coal left between the boring cutters of the machine.

Another object of the invention is to provide a unitary support, supporting rotary cutting means for cutting out the depending unmined cusps left between the boring cutters of a continuous mining machine, together with adjustable means for the support, vertically adjusting the rotary cutting means independently of the boring heads and supporting the support on the boring head support frame.

Still another object of the invention is to provide a continuous mining machine for coal and the like, in which a plurality of boring heads bore a plurality of intersecting bores in the working face of a mine, in which the unmined cusps of coal depending from the roof of the mine are cut out by rotary drum cutters, together with a unitary support for the rotary drum cutters, guided for vertical movement with respect to the boring heads, and power operated jacks for supporting the support and vertically adjusting the support with respect to the boring heads.

These and other objects of the invention will appear from time to time as the following specification proceeds and with reference to the accompanying drawings wherein:

Figure 1 is a view in side elevation of a continuous mining machine constructed in accordance with the invention;

Figure 2 is an enlarged front end view of the machine shown in Figure 1, with certain parts broken away;

Figure 3 is a fragmentary plan view of the forward end portion of the machine shown in Figure 1, with certain parts broken away and certain other parts shown in section;

Figure 4 is an enlarged fragmentary view in side elevation of the forward end portion of the machine, with certain parts broken away and certain other parts shown in vertical section;

Figure 5 is a fragmentary enlarged sectional view taken substantially along line V—V of Figure 3;

Figure 6 is a fragmentary sectional view taken substantially along line VI—VI of Figure 5; and

Figure 7 is an enlarged fragmentary detailed view illustrating the bit arrangement on the bearing support for the left hand rotary drum cutter for breaking off an edge of the cusp of unmined coal remaining after the boring operation.

In the embodiment of the invention illustrated in the drawings, Figure 1 shows a continuous mining machine 10 of the rotary boring type, in which a plurality of boring heads 11 may cut-out an entire seam of coal from the mine floor to the mine roof by driving intersecting bores directly into the coal face. The bores at their points of intersection leave two spaced upstanding cusps of unmined

2

coal extending upwardly from the mine floor, in the spaces between adjacent boring heads, and also leave similar cusps depending from the mine roof between adjacent boring heads. Spaced rotary drum type cutters 13 on transverse shaft 14, supported rearwardly of the boring heads 11, and rotatable about a horizontal axis extending perpendicular to the axis of rotation of the boring heads 11, are provided to cut along the mine roof in the spaces between the boring heads 11, to cut out the depending cusps of unmined coal and to provide a flat roof from one rib of the working place to the other.

The continuous mining machine is similar to that shown and described in my joint application with Frank Cartlidge Serial No. 665,062, filed June 11, 1957, and includes a main frame 15 supported on ground-engaging continuous traction tread devices 16 for supporting the machine from working place to working place and feeding the boring heads 11 into the working face of a coal seam.

A conveyor 19 extends along the main frame 15 from a position adjacent the ground in advance of the forward end portion and has an inclined apron 25 extending across the forward end thereof and forwardly therefrom to the ground and beyond opposite sides of said conveyor along which the mined coal picked up and loaded by gathering devices 20 onto said conveyor.

The gathering devices 20 are like those shown in my joint application with Frank Cartlidge, Serial No. 665,062, and generally include a pair of cutter bars 33 mounted on the apron 25 and extending forwardly along opposite sides of the conveyor 19 in the plane of the apron 25 and forwardly of said apron along the ground in parallel relation with respect to the ground, when the machine is in a cutting and loading position. Cutter bit carrying cutter chains 35 driven from individual motors 37 are guided 35 for travel about the cutter bars 33 (Fig. 4).

The forward end portions of the cutter bars 33 are positioned directly in alignment with the uncut portions left between the overlapping paths of cutting of adjacent mining heads 11, to completely cut out the cusps of uncut coal along the floor as the cutter chains pick up the mined coal from the ground and load it onto the receiving end of the inclined elevating portion of the conveyor 19, as in my aforementioned joint application with Frank Cartlidge.

The main frame 15 has spaced arms 40 and 41 extending along each side thereof, forwardly of the forward end thereof and along opposite sides of the traction tread devices 16 (Fig. 3). The arms 40 and 41 form outboard supports for a transverse beam 43, extending over the conveyor 19 in advance of the forward end of the traction tread devices 16. The beam 43 forms a support for an outboard gear housing or boring head support frame 44, supporting the boring heads 11 for rotatable movement about laterally spaced axes extending longitudinally of the machine.

Hydraulic jacks 45 mounted on the rear wall of the boring head support 44 and reacting against feet 46 projecting downwardly and forwardly of the beam 43 are provided to vertically adjust the boring head support frame 44 and the boring heads 11 mounted thereon, with respect to the ground. As herein shown, the jacks 45 are secured to the boring head support frame 44 and extend vertically along the rear wall thereof and have pivotal and sliding connection with the transverse beam 43, as shown and described in my application, Serial No. 671,792 filed July 15, 1957, and no part of the present invention, so not herein shown or described further.

A hydraulic jack 47 is trunnioned within the hollow interior portion of the beam 43 on trunnion pins 49 and has an extensible piston rod 50 pivotally connected between connecting ears 51 extending rearwardly from the rear wall of the outboard boring head support frame 44.

The jack 47 serves to maintain the boring head support frame 44 and boring heads mounted thereon in the desired angular relation with respect to the ground during and after changes in vertical height of said boring head support frame, and to tilt said boring head support frame to change the grade of the place being mined.

The boring heads 11 are well known forms of boring heads commonly used in boring types of continuous mining machines like those shown in the aforementioned joint application with Frank Cartlidge, so need only herein be shown and described in sufficient detail to render the present invention readily understandable. Each boring head 11 has an arm 67 extending radially from a hub 69 mounted on a hollow drive shaft 70. The arm 67 is of a fixed length and has an arcuate segment 71 extending forwardly of the outer end thereof, the arc of which is struck from the center of rotation of the arm 67. The arcuate segment 71 has circumferentially spaced cutter blocks and bits 73 extending forwardly therefrom.

An arm 75 extends from the hub 69 in a diametrically opposite direction from the arm 67. The arm 75 is hollow and has an arm 76 telescopically mounted therein and having an arcuate segment 77 extending forwardly from the outer end thereof. Cutter blocks and bits 79 extend forwardly of the arcuate segment 77. The arm 76 may be extensively and retractably adjusted with respect to the arm 75 and may be held in position with respect to said arm to vary the diameter of the bore, by means of a power driven screw type of adjusting mechanism, such as shown in Patent No. 2,272,870, dated December 4, 1956, and no part of the present invention so not herein shown or described further. A pilot cutter 80 extends forwardly from the center of the boring head 11 and has annularly arranged cutter blocks and bits 81 projecting forwardly therefrom in advance of the cutter blocks and bits 73 and 79. In Figure 2, the arcuate segments 71 and 77 and the cutter blocks and bits 73 and 79 of the three heads 11 are shown as being arranged out of phase with respect to each other, so that the path of cutting of one boring head intersects the path of cutting of the next adjacent boring head, to completely mine all of the coal in the coal face, except the upstanding and depending cusps of unmined coal spaced on opposite sides of the center boring head.

The boring heads 11 are driven from a motor and speed reducer 83 mounted on the main frame 15, through an extensible universal drive connection including spaced constant velocity universal joints 85 and an extensible drive shaft 86 connecting said universal joints together. The universal drive connection serves to drive reduction gearing (not shown) housed within the support frame 44 for driving the three boring heads 11 at the same rates of speed, as shown in my joint application with Frank Cartlidge, Serial No. 665,062, and no part of the present invention so not herein shown or described further.

The support means for the shaft 14 and the rotary cutters 13, supporting said cutters for vertical adjustment with respect to the boring head support frame 44, to accommodate adjustment of the rotary cutters 13 to conform to the arcs of cutting of the boring heads 11 comprises a vertically guided support plate 89 extending across the front of the boring head support frame 44 inwardly of the hubs 69 for the outer boring heads 11. The plate 89 has a recessed central portion 90 opening to the ground in registry with the hub 69 of the center boring head 11, to accommodate vertical movement of said plate with respect to said hub.

The plate 89 is shown as having spaced vertically extending slides 91 extending rearwardly of the rear face thereof and having inwardly inclined faces 93 facing outwardly and directed toward the support plate 89. The inwardly inclined faces 93 cooperating with the rear faces of the slides 91 form dovetail slides having slidable engagement with parallel spaced dovetail guides 95 project-

ing forwardly of and extending vertically along a front wall 96 of the boring head support frame 44, and retaining the plate 89 from tilting movement with respect to the front wall 96, and guiding said plate for vertical movement therealong.

The rotary cutters 13 on the shaft 14 are shown as being drum types of cutters having cutter bits 97 projecting outwardly from the faces thereof. The shaft 14 supporting and driving said cutters is journaled at one end, which is shown in Figure 5 as being its right hand end, on a ball bearing 99, mounted in a support arm 100 extending outwardly from the right hand end portion of the support plate 89. The shaft 14 is journaled intermediate its ends adjacent the inner end of the left hand cutter 13, on a ball bearing 101 mounted in a bearing cap 102, mounted in a support 103 extending forwardly from the plate 89 along the left hand wall of the recessed portion 90 and supported thereon. The support 103 forms one side of a gear housing 104, housing reduction gearing 105 for driving the shaft 14 and rotary cutters 13 in a cutting direction. A motor 106, herein shown as being a well known form of fluid operated motor is shown as being mounted on the plate 89 and as driving the gearing 105 through a motor gear 107 on the shaft for said motor. The gear 107 is journaled on a boss 108, extending inwardly from the support 103, on a ball bearing 109 (Figure 5).

It will be noted from Figure 5 that the rotary cutter 13, which is shown in this figure as being the left hand cutter is shorter than the right hand rotary cutter 13 due to the support 103 and gear housing 104. The left hand rotary cutter 13, therefore, does not entirely cut to the inner end of the cusp of uncut coal left by the center boring head 11. The uncut coal left between the inner end of the left hand rotary cutter 13 and the coal left by the center boring head 11 is shown as being cut by three chisel pointed bits 111, mounted in the top of the gear housing 104 and the support 103 and gouging a path through the inner portion of the cusp left by the left hand cutter 13 as the boring heads are advanced into the coal seam (see Figs. 5 and 7).

The means for vertically adjusting the plate 89 and rotary cutter 13 as a unit, to position the cutters 13 to cut along the mine roof in seams of varying heights, comprises two laterally spaced jacks 123, herein shown as being screw jacks, but which may be hydraulic jacks, if desired.

The jacks 123 are similar in construction so only one jack need herein be shown and described in detail. Each screw jack 123 comprises a screw 124 mounted at its lower end on a foot 125 extending forwardly of the bottom wall of the mining head support frame 44. The feet 125 are disposed inwardly of the outer boring heads 11 and the screws 124 may be welded or otherwise secured to said feet. Each screw 124 has a sleeve 126 threaded thereon and forming a nut for each screw jack.

The right hand sleeve 126 is shown as being journaled in a worm and worm gear housing 127 on a roller thrust bearing 129 abutting a lower shouldered portion 130 of the sleeve 126, and thereby preventing the sleeve from moving downwardly. The sleeve 126 is journaled in vertically spaced relation with respect to the bearing 129 on a roller thrust bearing 131 mounted in a housing and support 133, secured to and extending outwardly from the front face of the plate 89. The sleeve 126 is shown as having a bevel gear 135 cut integrally therewith adjacent the upper end thereof, and meshing with a bevel gear 136 mounted on the inner end of a transverse shaft 138, journaled adjacent its opposite ends in end plates 137 for the housings 133. The sleeve 126 is shown as being closed at its upper end and as having a lug 139 extending upwardly therefrom within a recessed portion of the upper wall of the housing 131, and journaled therein on a flanged bearing 142, the flange of which abuts the top of the

closed portion of the sleeve and serves as a thrust bearing.

The right hand sleeve 126 has a worm gear 140 keyed or otherwise secured thereto, within the housing 127 and driven from a worm 141 on a shaft 143 of a motor 145 mounted on the front face of the plate 89. The motor 145 is herein shown as being a well known form of fluid operated motor, although it may be any form of motor desired.

The shaft 138 has a bevel pinion (not shown) on the left hand end thereof, meshing with a bevel gear (not shown) on the left hand sleeve 126 and like the bevel gear 135. This will effect the driving of the two sleeves 126 at the same rates of speed in an obvious manner, and will thereby effect the elevating or lowering of the rotary cutters 13 upon operation of the motor 145, to position said cutters to cut along the mine roof in coal seams of varying thicknesses. The left hand sleeve 126 is exactly like the right hand sleeve except that it does not have a worm gear keyed thereto, and is journaled in a bearing housing 149 secured to and extending forwardly of the forward face of the plate 89.

The plate 89 has a ledge 150 extending forwardly therefrom between the housing 133 and over the transverse shaft 138 to protect said shaft from falling rock, coal and the like.

It may be seen from the foregoing that the plate 89 forms a unitary support for the transverse rotary cutters 13, the drive mechanism therefor as well as the elevating mechanism thereof, and the motor for driving the elevating mechanism. The entire transverse rotary cutter assembly, guided on the front of the boring head support frame 44 and supported and adjustably moved therealong on the jacks 123, may thus be removed from or assembled on the machine as a unit independently of the boring heads 11 and may also be adjustably moved independently of said boring heads to cut out the depending unmined cusps of coal at the proper elevation.

While I have herein shown and described one form in which my invention may be embodied, it will be understood that various modifications and variations thereof may be effected without departing from the spirit and scope of the novel concepts thereof as defined by the claims appended hereto.

I claim as my invention:

1. In a continuous mining machine for coal and the like, a plurality of boring heads rotatable about parallel axes extending longitudinally of the machine, a support frame for said boring heads, means for cutting out the depending cusps of coal left in the spaces between said boring heads comprising rotary drum cutting means extending transversely of said boring heads, means for supporting said rotary drum cutting means and vertically adjusting said rotary drum cutting means with respect to said boring heads comprising a plate extending across the front of said boring head support frame, guide means guiding said plate for vertical movement with respect to said support frame and retaining said plate from angular movement with respect thereto, spaced bearing supports projecting forwardly from said plate, a transverse shaft journaled therein and having said rotary drum cutting means mounted thereon, said transverse shaft and rotary drum cutting means being spaced rearwardly of said boring heads, power means for driving said shaft and rotary drum cutting means, and means for adjustably moving said plate along said guide means to position said rotary drum cutting means to cut along a mine roof comprising two laterally spaced jacks having screws mounted on said support frame adjacent the lower end thereof and having nuts rotatably mounted on said plate and retained from axial movement with respect thereto, means connecting said nuts to rotate together, and power means for driving said nuts to vary the elevation of said plate with respect to said boring head support frame.

2. In a continuous mining machine for coal and the

like, a plurality of boring heads rotatable about parallel axes extending longitudinally of the machine, a support frame for said boring heads, means for cutting out the depending cusps of coal left in the spaces between said boring heads comprising rotary drum cutting means extending transversely of said boring heads, means for supporting said rotary drum cutting means and vertically adjusting said rotary drum cutting means with respect to said boring heads comprising a plate extending across the front of said boring head support frame, guide means guiding said plate for vertical movement with respect to said support frame and retaining said plate from angular movement with respect thereto, spaced bearing supports projecting forwardly from said plate, a transverse shaft journaled therein and having said rotary drum cutting means mounted thereon, said transverse shaft and rotary drum cutting means being spaced rearwardly of said boring heads, power means for driving said shaft and rotary drum cutting means, and means for adjustably moving said plate along said guide means to position said rotary drum cutting means to cut along a mine roof comprising two laterally spaced screw jacks, each having a screw mounted on said support frame adjacent the lower end thereof and extending upwardly therealong, a nut threaded on each screw, vertically spaced housings for said nuts mounted on said plate and extending forwardly therefrom, thrust bearing means in said housings retaining said nuts from axial movement with respect to said housings, a transverse shaft journaled at its ends in the uppermost of said housings and connecting said nuts to rotate together, a motor mounted on said plate and extending forwardly therefrom, and a self-locking worm and worm gear drive from said motor to one of said nuts.

3. A rotary cutter assembly for mounting on the support frame of a boring type of continuous mining machine for cutting the depending cusps of coal left between the boring heads for the machine, comprising a plate, a transverse shaft extending across said plate adjacent the upper end thereof, bearing supports extending forwardly of said plate and supporting said shaft, at least one rotary drum cutter mounted on said shaft and driven therefrom, spaced slides extending vertically along the rear face of said plate for interengagement with corresponding guides on the support frame for the boring heads of the mining machine, laterally spaced screw jacks mounted on the forward face of said plate adjacent opposite ends thereof, and including nuts rotatably mounted on said plate and retained from axial movement with respect thereto, means connecting said nuts to rotate together, screws threaded within said nuts and adapted to be supported on the support frame for the boring heads of the mining machine and held from rotation with respect thereto, a motor mounted on said plate, and a self-locking geared drive connection from said motor to one of said nuts.

4. A rotary cutter assembly for mounting on the support frame of a boring type of continuous mining machine for cutting the depending cusps of coal left between the boring heads for the machine, comprising a plate, a transverse shaft extending across said plate adjacent the upper end thereof, bearing supports extending forwardly of said plate and supporting said shaft, at least one rotary drum cutter mounted on said shaft and driven therefrom, spaced slides extending vertically along the rear face of said plate for interengagement with corresponding guides on the support frame for the boring heads of the mining machine, two screw jacks mounted on said plate adjacent opposite ends thereof and including vertically spaced housings mounted on said plate adjacent opposite ends thereof and extending forwardly therefrom, a nut journaled in each set of vertically spaced housings and retained from axial movement with respect thereto, a transverse shaft journaled in the uppermost of

said housings and having geared connection with said nuts to connect said nuts to rotate together, a motor mounted on said plate, a geared drive connection from said motor to one of said nuts, and screws threaded within said nuts and adapted to be retained from rotation and to support said plate on the boring head support frame.

5. A rotary cutter assembly for mounting on the support frame of a boring type of continuous mining machine for cutting the depending cusps of coal left between the boring heads for the machine, comprising a vertically extending plate, a transverse shaft extending across said plate adjacent the upper end thereof, bearing supports extending forwardly of said plate and rotatably supporting said shaft, at least one rotary drum cutter mounted on said shaft and driven therefrom, a motor on said plate, means driven by said motor for driving said transverse shaft and cutter, spaced slides extending vertically along the rear face of said plate for interengagement with

corresponding guides on the support frame for the boring heads of the mining machine, laterally spaced vertically extending jacks mounted on the forward face of said plate adjacent opposite sides thereof, power means on said plate for simultaneously operating said jacks, and support means for said jacks on the support frame for the boring heads of the continuous mining machines supporting said plate and rotary drum cutter and the drive means therefor, for vertical adjustment with respect to the support frame for the boring heads of the continuous mining machine.
